RIDING TOY

Richard E. Ayres, 32501 Road 228, Woodlake, Calif.
Filed Nov. 9, 1959, Ser. No. 851,746

1 Claim. (Cl. 272—51)

The present invention relates to a riding toy and more particularly to a body supporting device adapted to revolve a rider supported on the device in an orbital path incident to shifting of the weight of the rider on the 10 device.

It is recognized that pleasure is derived from amusement rides that swing or revolve the rider in an orbital path about a fixed axis. This is evidenced by rides found at carnivals, provided by certain playground equipment, and the like. The known rides of this type are generally designed for group use, and may be power driven or may require pushing periodically to sustain rotation. The power-driven rides frequently have provision for jerking or "whipping" the rider during travel along the orbital path further to add to the thrill or excitement of the ride.

Many such rides are designed for use by large numbers of people. Because of the cost, size or difficulty of operation, for example, they are either impossible or impractical, for individual, home, or backyard use. Simplified, compact, light-weight, rider-driven toys which are same and simple to operate and use have not generally been available for carrying or sustaining the rider in an orbital path.

Accordingly, it is an object of the present invention to provide a revolvable riding toy.

Another object is to provide a body supporting device adapted to revolve freely in an orbital path incident to the shifting of weight of a body supported on the device.

Another object is to provide a revolvable riding toy which is simple and safe to operate.

Another object is to provide a revolvable body supporting toy adapted for individual as well as group use.

Another object is to provide a revolving seat in which rotation is motivated by shifting the weight of a rider supported on the device.

Another object is to provide a riding toy of the nature described which is compact, light-weight, and portable.

Another object is to provide a riding toy having a plurality of optionally employable riding positions affording a variety of experience.

Another object is to provide a body supporting device adapted to support a rider for movement in an orbital path and further adapted at his selection to impose a jerking or whipping action to the rider during movement along said path.

Another object is to provide a riding toy which requires some skill and agility to ride and which affords physical exercise for the rider.

Another object is to provide a riding toy adapted to carry the rider in an orbital path and in which the speed of travel along said path and the whipping action described above are controlled by the rider.

These, together with other objects, will become more fully apparent upon reference to the following description and accompanying drawing.

In the drawing:

FIG. 1 is a top plan view of the subject riding toy.

FIG. 2 is a somewhat enlarged, side elevation of the riding toy.

FIG. 3 is a still further enlarged, fragmentary section of a portion of the toy.

FIG. 4 is also a further enlarged, fragmentary cross-section of another portion of the toy.

Referring more particularly to the drawing, the riding toy of the subject invention includes a substantially circu-

2

lar, flat, rigid base disk 10 having an inner surface 11, an outer support surface 12, and a circular rim 13 concentric to an axis for the disk. An elongated tubular sleeve 16 provides an end wall 17 connected to the inner surface 11 of the base disk 10 so that the sleeve is coaxial with the disk. The base sleeve has a cylindrical side wall 18 providing a pair of transversely aligned apertures 19 and circumscribing a socket 20 open at the opposite end of the sleeve from the end wall.

A plurality of angle irons or gussets 25 individually provide mounting flanges 26 secured to the inner surface 11 of the base disk 10 by means of screws 27. The angle irons are radially extended with respect to the disk and are also in circumferentially spaced relation to each other. 15 The angle irons also have extended flanges 28 substantially normal to the inner surface of the base disk and provide inner ends 29 individually welded, or otherwise secured, to the side wall 18 of the base sleeve 16. The angle irons have outer ends 30 inwardly spaced from the rim 13 of the base disk. These angle irons impart rigidity to the base sleeve as well as to the base disk.

A flat, substantially circular, body supporting or seating disk 35 is also included in the subject riding toy and has an inner surface 36, an outer support surface 37, and a circular rim 38 concentric to an axis for the body supporting disk. Preferably, as best seen in FIGS. 1 and 2, the body supporting disk is slightly smaller in diameter than the base disk.

A coupling sleeve 45 includes an end wall 46 rigidly connected to the inner surface 36 of the body supporting disk 35 so as to mount the sleeve 45 in coaxial relation to the body supporting disk. The coupling sleeve has a tubular cylindrical socket 47 open at the opposite end of the coupling sleeve from the end wall 46. Elongated angle irons or gussets 49 have mounting flanges 50 individually secured to the inner surface of the body supporting disk by means of screws 51, extended flanges 52, inner ends 53 secured, as by welding, to the coupling sleeve 45, and outer ends 55 terminating short of the rim 38 of the disk 35. In essence, therefore, the body supporting and base disks are of substantially identical construction with the exception of the difference in diameter and the lack of transverse apertures in the coupling sleeve.

An obtusely angulated, journal or coupling rod 59 of cylindrical cross-section includes a supporting end portion 60 rotatably received in the socket 20 of the base sleeve 16. This supporting end portion has a transverse bore 61 extended therethrough which is alignable with the apertures 19 in the base sleeve when the supporting end portion is bottomed against the end wall 17 of the base sleeve. A coupling pin 63 is releasably extended through the aligned apertures and bore, and a wing nut 64 is screw-threaded on the pin for releasably holding it in place. The journal rod also has an opposite mounting or journal end portion 66 releasably rotatably received in the socket 47 of the coupling sleeve 45. In this manner, the disks are rotatably interconnected in acute angular relation to each other.

Operation

The operation of the described embodiment of the subject invention is believed to be readily apparent but is briefly summarized at this point.

The base disk 10 is rested on the ground or floor, not shown, in a substantially horizontal position with the support surface 12 facing downwardly. This, of course, supports the body supporting disk 35 in an upwardly inclined position with its support surface 37 upwardly disposed. It is evident that with the journal rod 59 pinned to the base sleeve 16, the body supporting disk is freely rotatable about its own axis on the mounting end por-

tion 66 of the journal rod. It is to be noted that the mounting end portion bears endwardly against the end wall 46 of the coupling sleeve 45.

A rider, not shown, is preferably seated on the support surface 37 of the body supporting disk 35 in squat position with his feed adjacent to the downwardly directed segment or low edge of the rim 38 and with his seat adjacent to the upwardly disposed segment or high edge of the rim. Further, the rider grasps the rim 38 with his hands on opposite sides of his body. As long as the rider's weight is equally distributed on opposite sides of a vertical plane normal to and diametrically of the body supporting disk 35, the latter remains stationary. A certain amount of resistance to rotation is also afforded by frictional contact of the coupling sleeve 45 with the mounting end portion 66 incident to the weight of the rider on the disk 35.

If the rider, not shown, desires to rotate the body supporting disk 35, he shifts his weight to one direction or the other causing an imbalance of forces on the upper portion of the body supporting disk and imposing a torque which rotates the disk in the direction toward which his weight is shifted. The rider thereby gravitationally swings from his original position, with his feet downwardly directed, to a reversed position with his feet directed upwardly and with his seat at the low edge of the disk. Inertia carries the seat of the rider beyond the lower point in the orbital path of travel. However, just before reaching said low point in said path, the rider swings his body in the direction of movement to impart an additional torque to the body supporting disk 35. This added torque plus the inertia carries the rider upwardly to his initial, feet-down position, and beyond, whereby the rider again descends. By repeating this action and properly shifting his weight, the rider can sustain rotation at considerable speeds. Each time the rider moves around the low point in the orbital path, he is subjected to a whipping or a jerking action. Both the speed and the extent of the whipping action can be controlled by the rider to suit his desires.

The subject riding toy can also be inverted whereby the body supporting disk 35 is supported on the ground in horizontal position and the base disk 10 is upwardly inclined. Obviously, therefore, the reference to the disks as being either base or body supporting is merely for the purpose of descriptive convenience and does not limit the position, use, or orientation of these disks. In the inverted position of the toy, it is to be noted that although the base disk is upwardly inclined, it does not rotate about its own axis but rather about the axis of the body supporting disk 35. The action of the base disk 10 in moving about the axis of the body supporting disk is one of nutation with the plane of the base disk constantly shifting as it revolves about the axis of the body supporting disk. It is evident, therefore, that a rider supported on the base disk receives an entirely different sensation during revolutionary movement from the sensation of riding on the toy with the body supporting disk in upwardly disposed position.

A still further use may be made of the subject toy. Thus, with either the base disk 10 or the body supporting disk 35 serving as the lower or horizontal disk, the pin 63 is removed by unthreading the wing nut 64. In this manner, both of the sleeves 16 and 45 are freely rotatable on their respective end portions 60 and 66. Assuming the body supporting disk 35 to be the upper disk, said disk is movable both about its own axis and about the axis of the base disk 10. The type of ride obtained when using the toy in this condition depends upon the

manner in which the rider's weight is imposed on the disks and upon relative frictional resistance to rotation of the end portions of the journal rod 59 in their respective sleeves.

While the operation of the subject toy has been described by stating that a rider is seated on the upper disk, it is to be understood that the toy can be ridden while lying down on the upper disk and shifting the weight, as before. Further, while the toy is primarily designed for the individual use, it is to be understood that the toy could be made in larger sizes and ridden by several persons at one time. In such an event, the operation of the toy would be essentially the same, it being understood that the various riders would shift their weights successively at the proper times during the travel around the orbital path.

From the foregoing it will be evident that a riding toy has been provided which revolves a rider in an orbital path and imposes a whipping or jerking action to the rider during a portion of travel along said path. The toy is particularly adapted for individual use and is highly appealing inasmuch as the type of ride can be controlled to a certain degree by the rider. The toy is light-weight, portable, compact, and safe to use. Further, the toy has several positions of use each offering a different type of ride. It is particularly enjoyable for children who not only experience the thrill and excitement of an unusual ride but also test their skill and agility and receive physical exercise as a result of use of the toy.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claim so as to embrace any and all equivalent devices and apparatus.

Having described my invention, what I claim as new and desire to secure by Letters Patent is:

An invertible riding toy on which a user may impart rotary motion to himself by successive periodic shifts of his center of gravity comprising a first substantially circular disk concentric to a first axis of rotation therefor, a second substantially circular disk concentric to a second axis of rotation for the second disk, a journal member having an elongated cylindrical mounting portion and an elongated cylindrical journal portion in obtuse angular relation to each other, second means rigidly coaxially mounted on the second disk and rotatably connecting the mounting portion of the journal member in concentric axially extended relation on the second disk, first means coaxially borne by the first disk and rotatably connecting the journal portion of the journal member in concentric axially extended relation on the first disk whereby the disks are in acutely angularly related planes and in opposed relation to each other with the journal member therebetween, and coupling means releasably interconnecting the second connecting means and the mounting portion of the journal member for preventing relative rotation between said second means and said mounting portion.
